UNITED STATES PATENT OFFICE.

EMANUEL EINSTEIN, OF NEW YORK, N. Y.

DESIGN FOR NAP-SURFACE OF CLOTHS.

SPECIFICATION forming part of Design No. 12,296, dated June 7, 1881.

Application filed March 14, 1881. Term of patent 3½ years.

To all whom it may concern:

Be it known that I, EMANUEL EINSTEIN, of New York, in the county and State of New York, have designed a new and original Design for the Nap-Surface of Cloths, of which the following, in connection with the accompanying drawing, is a full, clear, and exact description.

This design is related to that class of designs which are intended to be cut into the nap or pile of smooth-finished cloths in the act of shearing the same, such as is shown in the patent of Felix Samson, dated February 15, 1881, No. 12,176; and while these designs might be produced on the cloth in other ways than cutting, yet no other mode is contemplated or is so desirable, as a very agreeable and novel effect is obtained by the contrast of the sharply-cut grooves or figures with the smooth level nap of the cloth.

My present design is one of several of the aforesaid character filed on the same date as this; and it consists in a special form and arrangement of lines or grooves, producing a new effect, as hereinafter set forth.

The figure in the annexed drawing gives a face view of a piece of cloth finished according to my design.

In this figure the field of the design consists of the smooth or finished nap of the cloth, forming a uniform level surface, while the lines represent grooves cut into this nap.

My present design is composed of stripes of one or more straight lines, *aa*, extending longitudinally along the cloth at intervals, leaving

comparatively wide bands *bb* between them, which bands contain a bold to-and-fro zigzag groove or line, *cc*, extending lengthwise thereof, as shown. I prefer to have the zigzag lines of the several bands and the straight lines *aa* of the stripes so relatively arranged as to produce the appearance of broken squares or diamonds traversed centrally or diagonally by the straight lines *aa*. I also prefer to add portions of a second zigzag line, *d*, parallel to the first, between the entering angles of the main zigzag line and the straight lines *aa*, so as to give the appearance of smaller squares within the larger ones, but this is not essential. The angles of the zigzag lines may run into the straight lines, or they may end adjacent thereto, as illustrated. I prefer to form the dividing-stripes *aa* of two closely-adjacent parallel lines or grooves, as shown, but one or several of such lines may be used without altering appreciably the effect of the design.

The effect of the design, as may now be noted, is quite agreeable, as the straight and zigzag lines form a good combination and give diversity and liveliness to the effect.

What I claim is—

The design for the nap-surface of cloths, consisting of parallel stripes formed of straight lines, with intervening bands traversed by a to-and-fro zigzag line extending lengthwise thereof, substantially as described and shown.

EMANUEL EINSTEIN.
